GUN TURRET FOR MOBILE TANKS

Walter M. Pohl, New Haven, Conn., assignor to
 Vickers, Incorporated, Detroit, Mich., a corporation of Michigan

Application April 9, 1941, Serial No. 387,718

15 Claims. (Cl. 89—41)

This invention has to do with gun turrets for mobile tanks, and relates particularly to a system for the transmission of power in the manipulation and control of turret mounted guns. It is especially adaptable to gun turrets in mobile tanks such as used by military land forces.

An important object of the present invention is the provision of an efficient hydraulic system which enables an operator to control the movement of guns and turrets with a minimum amount of physical effort. This promotes greater dexterity in the control of the guns and makes it possible for the operator to hold on the target at all times irrespective of the motion of tank or target and makes it possible to readily compensate for the rolling and pitching motion of the tank due to irregularity in the terrain over which it is moving.

A further object is the provision of a servo-control device which will cause the movement of gun, or gun and turret to be responsive to the movement of the sighting scope.

Other features have to do with the individual and combined operation of the various elements incorporated in the system which will be more clearly brought out in the specification and claims.

In the drawings:

Fig. 1 is an elevation, partly in section, showing the operating units and controls mounted within a tank body and turret, in accordance with the present invention.

Fig. 2 is a plan view of the structure shown in Fig. 1.

Fig. 3 is a schematic diagram with the various operating and control elements as shown in Figs. 1 and 2 arranged in working relationship and shown in cross-section for better illustration.

Fig. 4 is an elevation similar to Fig. 1, illustrating a modified arrangement wherein the control and operating units are so positioned as to permit the operator to be seated in a stationary position instead of moving with the turret as in Fig. 1.

Fig. 5 is a plan view illustrating the position and arrangement of the control and operating elements of Fig. 4.

Fig. 6 is a schematic diagram showing the operating and control elements of Fig. 4 in operative relationship, the said operating and control units being shown in cross-section.

Fig. 7 is a horizontal sectional view of a stabilizing device which may be used in combination with the elevating control system as shown in Figs. 1 and 4 for automatically holding the gun

on a target while the tank is traveling over a rough terrain.

Figs. 8, 9 and 10 are enlargements, respectively, of the elevating and depressing motor, the training control, and the training motor shown in Fig. 3.

Fig. 11 is an enlarged portion of Fig. 6.

Although the drawings show tanks of smaller sizes, it will be understood that the equipment is readily adaptable to larger models.

For a clear understanding of the present invention it should be understood that the system embodies a power supply, or an A-end unit 18 (see Figs. 1 and 3), for pumping oil under pressure. This includes a variable stroke pump driven by a gasoline engine (not shown) which also supplies tractive power through transmission 12 to the tank and which is therefore subject to speed fluctuation. In order to compensate for these speed fluctuations and to maintain fluid output from the pump proportional to requirements, a flow control and pressure responsive compensator is incorporated in the A-end 18, as best shown in Fig. 3, and as will presently be described. Fluid from the pump is conveyed through conduits to control valves where it is diverted to fluid motors for manipulating a gun 15 and turret 13 at the will of the operator.

The principal elements of the tank as shown in assembly in Figs. 1 and 2 are a tank body 10, an engine drive shaft 11, a transmission gear case 12, a turret 13 movably mounted to rotate on the tank body about the vertical axis 14, and a gun or guns 15, movably mounted for rotation about horizontal trunnion axis 16, for elevation and depression, which trunnion in turn is in a fixed position with relation to the turret 13, so that gun and turret rotate together about vertical axis 14 for traversing or training the gun 15 and turret 13 at the will of the operator.

The A-end, or pump and tank unit 18, forms the power element of a hydraulic circuit, best shown in Fig. 3, and is mounted in a fixed position in the tank body 10 where it is arranged to receive power from the engine through belt 26 or other suitable driving means. Pressure oil from the pump passes through a suitable conduit to a swivel joint assembly 19, which is arranged to rotate about axis 14 so as to provide a means of conveying the fluid to the various other components, which are arranged to rotate with the turret 13. A hydraulic motor 20, or B-end, of standard type is carried by the turret 13 and provides a means for training the turret by transmitting torque through pinion 21 to ring gear

11 carried by the tank body. Speed and direction of rotation of the pinion 21 and the turret are controlled by manually operated valve 22.

Hydraulic force for elevating and depressing the gun is provided by hydraulic assembly 23, which is attached to the turret at one end by pivot 27 and to the gun at its other end by pivot 28. Speed and direction of motion of the gun are controlled by means of a valve located within the cylinder assembly 23 and arranged for manual operation through signal means comprising linkage 26 connecting it to the sighting scope assembly 26a.

The mechanics of operation will be better understood by referring to schematic diagram of Fig. 3. In the A-end unit 18, a variable delivery pump 29 of standard construction has a shaft 36, which is driven continuously in the direction indicated by the arrow. Oil is delivered from the pump into a conduit 32 at a rate proportional to the angular displacement α of a movable member 31, which determines the pump stroke. The stroke is automatically controlled by means of spring-loaded pressure responsive piston 33, which is designed to limit the power input by maintaining certain functional values between oil pressure and volumetric delivery. For example, as pressure tends to increase, the spring force against the piston 33 will be overcome in varying degrees, thus reducing the stroke in proportion to pressure. When the maximum pressure is reached for which the spring is designed, the stroke will be reduced to a point near zero, at which point the volumetric delivery will just equal the leakage in the system. This device not only protects the hydraulic system against excessive pressure, but it also prevents overloading of the engine by limiting the power input demand of the pump. As a further protection to the hydraulic system, an emergency relief valve 34 is incorporated in the pressure line. This relief valve is designed to open and dump the entire flow of the pump into the supply tank in case the compensator fails to function when the maximum pressure is reached.

The maximum flow from the pump is limited to a predetermined rate by throttle valve 35 and hydrostatic valve 36, through which the oil must flow in passing from conduit 32 to conduit 37. The hydrostatic valve 36 is constructed with a piston portion 38 with equal pressure areas on both sides. It is normally held open by the light spring 39 when the hydraulic pressure on both sides of the piston are equal, but will close and block or restrict the flow of oil to conduit 37 when a slight pressure differential exists on the upper side of the piston. Throttle valve 35 is designed to produce such pressure differential when the speed of the engine reaches a point where the delivery of the pump exceeds the predetermined value. This automatic function is accomplished by adjusting the throttling valve to a position where it will permit free flow for the normal requirements of the hydraulic motors 20 and 23, but when this rate of flow is exceeded, the resulting pressure drop across the throttle will cause valve 36 to close and restrict the flow of oil into conduit 37.

The closing of valve 36 will result in a pressure rise in conduit 32 which will react through the compensator to reduce the pump delivery by shortening the pump stroke. After the pump stroke has shortened sufficiently to compensate for the increased engine speed, the pressure differential on valve 36 will be neutralized and the

valve will open to its normal position. This process will be repeated as often and as rapidly as necessary to maintain constant maximum flow to the operating system.

5 It will appear obvious that the throttle valve 35, operating in combination with the compensator, is the essential element in controlling the rate of flow from the pump and that valve 36 is a secondary element which is incorporated to render the device more responsive to slight increases in the flow rate.

10 Swivel joint assembly 19 provides a means for conducting the oil from the unit located in a fixed position in the tank body to the units located in the rotatable turret. It consists of a member 40 fixedly mounted on the tank body and to which the fixed pipes are attached, and a movable member 41 to which the rotating pipes 43, 50 and 52 are attached.

15 20 Fluid pressure in conduit 37 is conducted to an elevation control valve 44 and a training control valve 46 through annular groove 42, conduit 43, and conduit 45. Both of these valves are shown in the closed position, in which position they block all flow from the pump. Under this condition the pump 29 will be set on zero stroke by the compensator, but full operating pressure will exist in the conduits, so that both pressure and volume will be made available to the hydraulic motor 20 or cylinder 23 upon opening one of the control valves 46 or 44.

25 30 The training movement of the turret is initiated and controlled by moving control valve 46 by means of handle 46a in the direction in which the training movement is desired. To train right, valve 46 is moved to the right where it admits pressure through conduit 47 to hydraulic motor 20 where it is converted into torque to rotate pinion 21 on ring gear 17, thus training the turret to the right.

35 40 The exhaust fluid from the hydraulic motor passes through conduit 48 to valve 46 where it is metered through tapered grooves 52 (Fig. 9), which provide a means of controlling the training speed in proportion to the displacement of valve 46. Exhaust flow from valve 22 is then returned to the supply tank through conduits 49, 50, and 51. Training to the left is accomplished by shifting the control valve 46 to the left to reverse the direction of flow to hydraulic motor 20.

45 50 Conduit 55 provides a means of returning excess oil from gear case 53 to the supply tank through swivel joint 19 and conduit 54. It will be noted that conduit 55 projects upward into the gear case to serve as a stand pipe, so as to maintain a constant oil supply in the case for lubricating the gearing.

55 60 Clutch 55 provides a driving connection between hydraulic motor unit 20 and training pinion 21. In case of power failure the turret may be trained manually by attaching a crank to shaft 55a. In this event the clutch may be temporarily disengaged so as to eliminate the resistance of the liquid in the hydraulic system during training movement. The clutch is shifted by means of hand lever 56.

65 70 The movements of the gun, in elevation and depression, are entirely responsive to the movement of sighting scope 58, which, as best shown in Fig. 3, is manipulated by pistol grip 57. Scope 58 is mounted on a horizontal pivot 58a which in turn is mounted on a vertical pivot 58b. This motion is transmitted through the control plunger 83 and interconnecting linkage or signal means 25 between the sight scope and spigot

controlled valve 44, which controls the flow of oil into cylinder 28.

In operation, to elevate the muzzle of the gun the pistol grip is manipulated so as to move the fore end of the sight upward. This causes valve 44 to be shifted upward where it admits pressure to the lower end of pressure chamber 59 of the cylinder and vents chamber 60 to tank through conduits 50 and 51. The arrows along linkage 25 illustrate the movement for muzzle elevation. The gun will then move in elevation so long as the sight continues to move in that direction. When the sighting scope comes to rest on the target, valve 44 will also come to rest and the follow up movement of the gun will cause the ports in cylinder 28 to overtake the valve and block the passage of oil to or from chambers 59 and 60, thus bringing the gun to rest on the target. Adjusting screw 61 is incorporated in the control linkage as a means of providing parallax correction between gun and sighting scope in the vertical plane. Adjusting screw 62 (see also Fig. 2) provides a means of correcting for parallax in the horizontal plane. Electric wiring 63, shown leading from the forward end of the pistol grip, is for connection to the firing circuit, not shown.

In case of power failure, the gun may be controlled manually by grasping the stock. Under this condition the bypass valve 64 may be temporarily shifted to the manual position where it bypasses the oil in chambers 59 and 60 to eliminate hydraulic resistance to the movement of the gun during elevation and depression.

In the modification shown in Figs. 4, 5 and 6, the elements and their functional relations with each other are similar to those described above, and similar numbers refer to similar parts on the two schematic diagrams. The principal difference between the operating and control elements in Figs. 4, 5 and 6, and the one previously described, with particular reference to Figs. 1 and 3, is in the arrangement of the various units. In the arrangement shown in Fig. 4 the operator sits at a fixed control station in the main body of the tank, from which point he controls the movement of the gun and turret. It will also be noted that the hydraulic motor assembly 20b for training the turret 13b is likewise mounted in a fixed position on the main body 10b of the tank and that the training ring gear 17b is fixed as a part of the turret. This method of mounting the hydraulic motor 20b is desirable in the present arrangement in order to simplify the piping system and control mechanism.

The elevation and depression mechanism is the same as previously described in connection with Figs. 1 and 3, with the exception of the control linkage 25b, which, as best shown in Fig. 6, is designed to permit linear motion to be transmitted from the fixed control station and handle 57b through the swivel joint 19b to control valve 44b.

The essential difference in the training mechanisms between Figs. 1 and 4 is the incorporation of a follow-up and response device in the modification shown in Fig. 4. The training motion is controlled by valve 65, which is designed for linear movement in a valve body 22a, but it is normally held in the neutral position, as shown by the centering spring 66. In this position it blocks the pump pressure line 67 and hydraulically locks the turret in position by blocking both conduits 69 and 70 of the hydraulic motor.

Linear motion is transmitted to valve 65 by rotating the helix 71 in the response gear 72.

This rotary motion is transmitted from the sighting scope assembly through gears 73, 74, 75, 76 and slip joint 77. The slip joint is designed to transmit rotary motion to the helix without restricting the linear movement. Response motion is transmitted from the turret ring-gear 17b to gear 72 through gears 78, 79, 80, shaft 81, gear 82.

In operation, movement of sight 53b and gear 73 results in movement of the valve 65 which is shifted in a linear direction to open and admit pressure to the hydraulic motor 20b, through one or the other of conduits 69 or 70, depending upon the direction of motion desired. The response motion of the turret and shaft 81 then tends to reverse the valve and shut off pressure. In this manner training motion of the turret and sighting scope are synchronized and are equal in speed, amplitude, and direction of rotation. This principle will be more readily understood by studying the operation for training in one direction.

Let it be assumed that the turret is to be trained to the right, that is, in a clockwise direction as viewed in Fig. 5. Moving the pistol grip 57b to the right rotates helix 71 in the direction which causes valve 65 to move forward where it admits pressure to hydraulic motor 20b through conduit 69. This pressure is converted into torque at the hydraulic motor 20b, thus causing the turret 13b to rotate in the clockwise or "train right" direction. Exhaust flow from the hydraulic motor 20b returns to the control valve through conduit 70 and from there it is diverted to the supply tank through conduits 68 and 51b. As the training movement continues, the response mechanism of the turret and shaft 81 and connecting gears will tend to drive or rotate gear 72 on the helix and return valve 65 to its neutral position. This response motion, however, will be effective in closing the valve only in the event the training motion of the sighting scope is arrested; for so long as the sighting scope continues to move, gear 72 and helix 71 will rotate together and there will be no relative motion between them.

By correlating the above analysis of operating principles of the modification shown in Figs. 4, 5 and 6 with those of the elevating mechanism previously explained in connection with Figs. 1, 2 and 3, it will be seen that the follow-up arrangement shown in Figs. 4, 5 and 6 provides a means for synchronizing the gun with the sighting scope in both training and elevating, and for controlling the same by means of a single control lever or pistol grip 57b.

The operating principles in training left are similar to those just described for training right.

Fig. 7 is a fragmentary plan of a stabilizing device which is designed to be incorporated in the control mechanism of the elevating system for the gun in such manner as to compensate for any pitching motion of the tank which may be caused by irregularities in the terrain over which the tank is passing. The drawings represent the top plan of the device as it may be installed as a part of the control mechanism shown in Fig. 2. Pistol grip 57c is indirectly connected to the sighting scope control plunger 83, of the control valve mechanism through differential gearing 84. The third element 88 of the differential is connected to an inertia device 85 through gears 86 and 87 so that it is constantly held in a fixed plane. A gyroscopic device 85 has a torque axis 85a leading to gear 87. The spinning axis is at 85b while the inertia wheel 85c lies in a horizontal plane. Any movement of the tank

from horizontal will cause shifting of part 88 to horizontal to effect correction. It will be understood that the housing carrying the differential gearing may form a part of the sighting scope assembly housing 25a, or at least is like the sighting scope assembly fixedly positioned relative to the turret 13. The inertia device is preferably of the gyroscopic type, which will maintain itself in constant alignment in a fixed plane.

With the stabilizing device of Fig. 7 forming a part of the control structure shown in Figs. 1, 2 and 3, and with the third element of the differential restrained from rotation by the inertia device, it will be readily understood that any movement of the pistol grip 57b will be transmitted through the differential gearing to plunger 83 and to the control valve link 25, for bringing the gun on the target. It will also be understood that any deviation of the tank from the plane which it was in at the time the gun was pointed will tend to move the gun off the target. The alignment of the inertia device, however, will not change from its original plane and under such conditions it has the effect of introducing a correction factor proportional to the misalignment of the tank, so that the gun and sight will be held on the target, irrespective of the pitching motion of the tank.

It will be understood that the stabilizing device as illustrated in Fig. 7 may be added to the control unit of the modification illustrated in Figs. 4 and 6. In this case the actuation of the control lever 25b and the control gear 13 14 would be by means of a pistol grip through differential gearing.

An important feature of the designs as shown in Figs. 3 and 6 is the arrangement of the control valves and synchronized operating levers to produce an effective anti-kick against the recoil of the gun or guns. As best shown in Fig. 3, the control linkage 25 and the ports connecting the control valve 44 with the chambers 59 and 60 are so arranged that when the pistol grip 57 is moved upwardly for elevation, valve 44 is likewise moved upwardly to direct fluid pressure to the chamber 59. If the gun is fired when the telescope 58 is "on" the target, the valve 44 will be in neutral, the ports will be closed and any recoil will be absorbed by the oil in the cylinders; however, if the gun is fired as the same is being elevated, or for any reason the gun is moving counter-clockwise about the trunnions 16 at the time of firing, the counter-clockwise movement of the valve casing 23 will tend to move the valve 44 downwardly to close the valve, or move it to a point to admit liquid to the chamber 60, thus in either case tending to counteract recoil of the gun. If the gun should be fired while the pistol grip is moving downwardly, which would be depression movement of the muzzle of the gun, recoil would move the valve 44 downwardly relative to the casing 23 and would tend to keep the valve open so that oil under pressure would continue to flow to the chamber 60, thus counteracting the recoil action.

The anti-kick action of the elevating-depression actuating and control members as shown in Fig. 6 is essentially the same as that above described with specific reference to Fig. 3. In addition, the control valve 22b, its associated parts, and the response mechanism for controlling the training movement, are so arranged and correlated that effective anti-kick action is obtained against the firing of only one of the guns, as shown in Fig. 5. If the pistol grip 57b and the

telescope 58b are stationary as far as training movement is concerned, valve 65 would be closed and the trapped liquid would prevent or subdue kick back or over haul such as would be caused by the firing of a single gun which would tend to cause whip of the gun about the vertical axis of the turret. If the gun 15b should be fired while the turret is training to the right, there would be a tendency for the turret and the gun to whip to the right and this motion transmitted through the shaft 81 and gears 82, 72 would move the valve 65 towards closed position to immediately set up reaction against further whipping or over haul movement of the turret. On the other hand, if the gun 24 should be fired during this right hand training movement, the first instantaneous reaction would be to cause further opening of the valve 65, thus directly counteracting the tendency of the gun and the turret to whip to the left. As will be readily seen in Fig. 6, the valve 65 and the response mechanism connecting the same to the turret are so designed and arranged as to prevent or subdue kick back or over haul due to firing of one or the other of the guns during training movement to the left, in the same manner as above described with respect to training to the right.

What I claim is:

1. In an army tank, a stationary portion, a movable gun supporting portion, a source of liquid under pressure in said stationary portion, motors in said movable portion for shifting the same and elevating a gun mounted thereon, conduits connecting said motors with said pressure source, means in said conduits for permitting movement of said movable portion relative to said stationary portion comprising a central stud formation mounted on said stationary portion having conduits extending upwardly therein connecting with ports in the outer surface thereof, a portion mounted on said movable portion surrounding said stud having ports therein adapted to register with the ports in the surface of said stud, and conduits connecting the ports in said surrounding portion with the conduits of said movable portion, an operating scope on the stationary portion of the tank, follow valve means on said turret for controlling the elevating motor and linkage connecting the scope and the follow valve for operation of the valve, a portion of said linkage passing centrally through said stud and having longitudinal movement therein and serving as signal and response mechanism.

2. In an army tank, a revolving gun turret, a trunnion mounted gun on said turret, means for effecting the movement of said turret relative to said tank, a sighting scope on said turret mounted independently of said gun, a source of hydraulic pressure, a motor for elevation adjustment of said gun comprising a piston and rod suspended from said turret, a cylinder on said gun to the rear of the trunnion thereof in which said piston is located, a valve block also movable with said gun connecting said pressure source with said valve block, means connecting said valve block with the respective ends of said cylinder, and linkage connecting said scope and said valve and block whereby movement of said scope will cause shifting of said valve, said valve being designed to direct pressure to one end or the other of said cylinder depending on the direction of movement of said scope, said linkage constituting not only a signal means from said scope to said valve but also a response mechanism whereby movement of said gun is directly pro-

portional to the movement of said scope in a follow-up arrangement.

3. In an army tank, a movable gun turret mounted thereon, hydraulic motor means for shifting said turret, a gun movably mounted on said turret and hydraulic motor means rigidly connected to said gun and pivotally supported from said turret for shifting said gun to properly elevate the same, means in said turret for carrying an operator, a scope mounted on said turret to be manually adjusted by said operator, a source of hydraulic pressure, control means for directing pressure to each of said motors to effect training of said gun and elevating of the same, signal means connecting one of said control means to said scope whereby elevation adjustment of said scope will effect simultaneous elevation of said gun, and a response mechanism operably connecting said gun and said control means whereby movement of said gun is directly proportional to the movement of said scope, and stabilizer means comprising a differential interposed in said signal means and a gyroscopic element connected to one element of said differential whereby change of level of said tank will impart correcting signals to said control means to maintain the aim of said gun.

4. In an army tank, a rotatable gun turret and a combined hydraulic and manually operated gun mounted on said turret, piston and cylinder structure connecting the turret and a portion of the gun for hydraulically supporting and controlling the movement thereof, and a follow up type control valve for controlling the flow of operating liquid to said piston and cylinder structure, and by-pass means to connect the ends of the cylinder to allow interflow of said operating liquid thus permitting manual operation of the gun.

5. In an army tank, a rotatable gun turret and a combined hydraulic and manually operated gun mounted on said turret, piston and cylinder structure connecting the turret and a portion of the gun for hydraulically supporting and controlling the movement thereof, a follow up type control valve connected to and movable with said cylinder for controlling the flow of operating liquid to said piston and cylinder structure, means to permit manual operation of the gun comprising by-pass conduits for operating liquid in said cylinder, and centering means for said follow up valve for positively insuring centering of the valve parts when the gun is stationary.

6. In an army tank of the type having a rotatable gun turret and a gun carried thereby, hydraulic motors for training the turret and gun and for elevating and depressing the gun, at least one of said motors being movable with said turret, a follow-up control valve integrally connected to and movable with said last named motor, a sighting scope, directional means directly connecting said scope and said valve for obtaining synchronous movement of the scope and gun, a source of pressure supply mounted in a fixed part of the tank, and distributing means for conducting fluid under pressure from said pressure source to one or more of said movably mounted motors.

7. In an army tank, a rotatable gun turret, a source of hydraulic pressure, a hydraulic motor carried by the turret and hydraulically supporting one or more guns for elevating and depressing the same, and a manually controlled valve of the follow up type integrally connected to and movable with said motor for controlling the flow

of operating liquid to and from said motor and for directing said gun, said valve and said motor being so arranged as to prevent or subdue kick back due to firing of the gun or guns whether the gun is fired when stationary or during elevation or depression thereof.

8. In an army tank, a rotatable gun turret, a hydraulic circuit including a source of pressure supply and a hydraulic motor for controlling training of the turret and the gun or guns therein, and a confined hydraulic motor and control valve pivotally mounted on said turret and operatively connected to said gun or guns for elevating and depressing the gun or guns, a sighting scope, gun directing means directly connecting said scope and elevating motor and control valve and indirectly connecting said scope and training motor through a follow up type valve for controlling movement of the gun and whereby movement of the gun and scope are synchronous and controlled by said single directing means.

9. In an army tank, a rotatable gun turret, a hydraulic circuit including a source of pressure supply and a hydraulic motor for controlling training of the turret and the gun or guns therein, and a combined hydraulic motor and follow-up valve operatively connected to said turret and said gun or guns for elevating and depressing the gun or guns, a sighting scope, a single gun directing means directly connecting said scope and said combined motor and valve and indirectly connecting said scope and training motor through a follow up type valve for controlling movement of the gun and whereby movement of the gun and scope are synchronous and controlled by said single directing means, the connecting means between said directing means and follow up valves being such that training and elevating movements are controlled entirely by movement of said single directing means by the operator, said follow up valves including response means for centering the valve member to the respective follow up valves when either or both of said movable members catches up with movement of said directing means, said follow up valves, connecting means and response means being so arranged as to prevent kick back of the gun and prevent kick back or overhaul of the turret due to the firing of a wing gun in a multiple gun installation.

10. In a land tank, a rotatable gun turret and a combined hydraulic and manually operated gun mounted on said turret, piston and cylinder structure connecting the turret and a portion of the gun for hydraulically supporting and controlling the movement thereof, a follow-up type control valve for controlling the flow of operating liquid to said piston and cylinder structure, means for manual manipulation as a control lever, and linkage connecting said means and said valve serving as a signal means to said valve and also as a response mechanism to reflect movement of said gun and limit movement thereof to a proportional amount of the movement of the manual means.

11. In a land tank, a rotatable gun turret and a combined hydraulic and manually operated gun mounted on said turret, hydraulic motor means for elevating the gun or rotating the turret, a source of liquid under pressure comprising a variable delivery pump and compensating means thereon including a constant volume flow control valve for effecting constant flow delivery from said pump, a follow-up control type valve for each of the motors controlling the flow of

liquid from the source of pressure to the motors, a means for manual manipulation as a control lever, and linkage connecting said means and said valve serving as a signal means to said valve and also as a response mechanism to reflect movement of said gun and limit movement thereof to movement of the manual means.

12. In an army tank of the type having a rotatable covering gun turret for carrying an operator and a gun supported therein, a hydraulic motor pivotally suspended on the turret above the operator's position and operatively connected to the gun for elevating and depressing the gun, a follow-up control valve connected to and movable with said gun, a sighting scope, and directional means directly connecting said scope and said valve for obtaining synchronous movement of the scope and gun.

13. In an army tank of the type having a rotatable covering gun turret and a gun supported therein, a hydraulic motor having one of two relatively movable elements pivotally suspended on the turret and the other operatively connected to the gun for elevating and depressing the gun, a follow-up control valve integrally connected to and movable with the element of said motor which is connected to the gun, a sighting scope, and directional means directly connecting said scope and said valve for obtaining synchronous movement of the scope and gun.

14. In a land tank, a rotatable gun turret and a combined hydraulic and manually operated gun mounted on said turret, piston and cylinder structure connecting the turret and a portion of the gun for hydraulically supporting and controlling the movement thereof, a follow-up type control

valve movable with said gun for controlling the flow of operating liquid to said piston and cylinder structure, a sighting scope, means for manual manipulation as a control lever, and linkage connecting said means and said valve responsive to movement of the manual control lever to shift said valve and operable upon movement of the gun to stabilize the valve position and thus reflect movement of said gun and limit movement thereof to a proportional amount of the movement of the manual means, and means to adjust the relationship between said control lever and said linkage signal means to correct for parallax differences between said sighting scope and said gun.

15. In an army tank, a rotatable gun turret, a hydraulic circuit including a source of pressure supply and a hydraulic motor for controlling training of the turret and the gun or guns therein, and a combined hydraulic motor and control valve pivotally mounted on said turret and operatively connected to said gun or guns for elevating and depressing the gun or guns, a sighting scope, gun directing means directly connecting said scope and elevating motor and control valve and indirectly connecting said scope and training motor through a follow up type valve for controlling movement of the gun and whereby movement of the gun and scope are synchronous and controlled by said single directing means, and means to adjust the relationship between said scope and said follow up valve to correct for parallax differences between said scope and said gun or guns.
